UNITED STATES PATENT OFFICE.

WILLIAM C. DOWNING, OF CHICAGO, ILLINOIS.

COMBINATION TICKET-PUNCH.

1,233,456.

Specification of Letters Patent. Patented July 17, 1917.

Application filed September 29, 1913. Serial No. 792,434.

To all whom it may concern:

Be it known that I, WILLIAM C. DOWNING, a citizen of the United States, residing at Chicago, in the county of Cook and State of Illinois, have invented certain new and useful Improvements in Combination Ticket-Punches, of which the following is a specification.

This invention relates to improvements in combination ticket-punches and pertains more especially to that class of devices which are the subject-matter of a number of patents, heretofore granted to me.

The general object of this invention is to provide a device of this character that will compel a conductor or ticket collector to keep a complete and accurate record of all fares collected, and thereby guard against the possibility of fraudulent practices.

20 The advantages embodied in this invention are numerous and by way of a practical illustration the different forms of transportation may be classified as follows:

First. Tickets collected.

25 Second. Cash fares.

Third. Tickets collected and turned over to next conductor.

Fourth. Card passes.

30 Fifth. Commutation tickets with punch margin.

Every ticket, mileage slip, trip pass or coupon collected is canceled and stamped with a designating number, and the hat-checks issued against the transportation collected must bear the imprint of the next higher number. In this way for every hat check issued a ticket must be canceled and numbered and there can be no "holdover" tickets to be saved and used to cover up cash fares or for other fraudulent purposes, as the tickets must be canceled and numbered in the order collected or else a hat check cannot be properly issued without a record having first been made of the ticket last taken up. An additional safeguard is provided in the fact that if cancellation numbers 23 and 27 are both on tickets from Chicago, a cash fare No. 25 would, in the regular order of procedure, be from Chicago, as well; while the hat check No. 26 would give the destination of the passenger.

In the collection of cash fares, suppose the usual cash slip retained, is stamped with an odd number, then the hat check following will show the next higher even number, so

that no "hold overs" can be worked in, for each fare must be definitely and finally registered in its own proper turn.

In the use of passes, the report slip is 60 stamped and a numbered hat check issued to the holder of the pass. This stops false pass reports and prevents collectors from using pass numbers to cover up cash fares.

The conductor or fare collector will stamp 65 his beginning and closing number on his report to the auditor for each day or trip and all intervening numbers must be accounted for.

This provides a system whereby every 70 passenger has a hat check, and some kind of transportation must be canceled and registered before a hat check can be properly issued. It will be understood that if the first ticket or fare collected be given an odd number, the hat check will bear an even number. This order may be reversed in accordance 75 with what number the machine may be set at when the initial operation begins.

The device can also be used for a straight 80 registration of fares without issuing hat-checks, or register all fares and issue hat-checks for cash and mileage, or register all fares and issue numbered hat-checks for all passengers.

85 In general the device is adapted to conform to all the rules and requirements of different roads and using the present forms of transportation.

Fig. 20 is a detached detail of a movement and locking pawl.

Fig. 21 is a vertical section on line 21, 20 Figs. 16 and 17.

Fig. 22 is a horizontal section on line 22, Fig. 8.

25 Fig. 23 is an elevation of a portion of the actuating lever-handle and the casing plate-part thereof looking at the inner side.

30 The machine casing incloses and supports the working mechanism and comprises a stationary part A and a movable round plate-part B. The part A is provided with a rigid handle C and the movable part B with an actuating lever-handle D. The two parts, comprising the casing, are operatively secured together by a pivot-pin 2, extending therethrough from side to 35 side, as best shown in Figs. 1, 2, 3, 4, 5, 6 and 7.

40 The extended front end of the stationary member of the casing A is provided with a barrel head-part 3 in which is located a series of numbering or printing wheels, and which in this instance consists of a units-wheel 4, a tens-wheel 5, a one hundreds-wheel 6 and a thousands-wheel 7, as best shown in Figs. 5 and 6. An axial-shaft 8 45 extends through the head-part 3 at the front end of the casing A and is provided with suitable bearings therein. This axial-shaft is limited to a rocking or partial turning movement in the operation of actuating the units-wheel and other elements 50 associated therewith. The units-wheel 4 is provided on its outer side with a ratchet-wheel 9 formed integral therewith, but of a less diameter and is shown in Figs. 10, 55 11, 12, 13 and 21. The units-wheel is loosely mounted on its axial-shaft. A movement disk 10 is rigid on the axial-shaft 8 and seats inside of ratchet-teeth 11, of the ratchet-wheel 9 and which extend 60 out over the same, as best shown in Figs. 5, 6 and 21. The disk 10 is provided with a cavity 12 in which a spring 13 is seated and on which the inner end of a movement pin 14 rests, as best shown in Figs. 10 and 65 11, the spring and cavity being also shown

in Figs. 21 and 22. The outer end of this pin has a continuous frictional contact with the inner circumferential surface of the ratchet-teeth 11 and acts to transmit an impulse turning movement to the units-wheel at the proper time. The normal position of pin 14 is shown in Fig. 10, and the opposite position in Fig. 11. The normal position of pin 14 corresponds to the normal open position of the actuating lever-handle D.

70 A cavity 15 is formed in the stationary part of the casing over the units-wheel and has a spring 16 inserted therein, as shown in Figs. 5, 6, 10 and 11. The outer end of a locking-pin 17 extends into said cavity and bears against said spring; the inner end of this pin riding loosely on the outer side of the ratchet-teeth 11 and is yieldingly held in contact therewith by the 75 spring 16. The pins 14 and 17 coöperate in actuating the units-wheel and fixing the 80 true position thereof after each impulse movement. The operation and function of these particular parts will be explained 85 farther along.

90 When all the parts are in their normal position, the key-seats 18, in shaft 8, are in diagonal relation with reference to the axis of rotation, as shown in Figs. 10 and 12, 95 and in the vertical position shown in Fig. 11, when the lever-handle is in its closed position.

99 In the normal position shown in Fig. 10, the movement-pin 14 occupies an inclined 100 position so that a part of the outer end of the pin bears against the under side of one of the ratchet-teeth 11, and the other part rests in one of the notches 19 between the teeth 11. When the lever-handle is moved 105 inward the axial shaft and the disk 10 are turned to the position shown in Fig. 11. With this movement, the pin 14 is compressed against the pressure of its spring by the particular ratchet-tooth against 110 which it has an end bearing and rides underneath the same to the position shown in Fig. 11. In this position the pressure of its spring returns the pin 14 into engagement 115 with the next succeeding notch 19 and has a side bearing against the ratchet-tooth back of it. During this back movement of the axial shaft and disk 10, the beveled end 20 of locking pin 17 rides up over the inclined surface 21, of the particular ratchet-tooth with which it is in contact, and drops down and bears against the straight wall face 22 of the tooth and locks the units-wheel and its ratchet-wheel 9 against further back movement. It will 120 be understood that in the position shown in Fig. 11, the actuating lever-handle D is in its innermost closed position, the stop-shoulder 23 thereof coming to a stop against a corresponding shoulder 24 125 130

formed on the rigid handle part C, near its junction with the stationary part of the casing A.

The stationary casing part A is provided with a stop-ledge E, as best shown in Fig. 1. The movable turning part B of the casing is provided with a shoulder F as shown in Fig. 23. On the return to normal position when the closing pressure on the actuating lever-handle is relaxed, the shoulder F comes to a positive stop on the ledge E, limiting the outward movement of the handle-lever and prevents injury to the finer parts of the mechanism.

The mechanism for transmitting a turning or rocking movement to the axial-shaft 8, through the movement of the actuating handle will be next described.

The inner end of shaft 8 extends into a chamber 25 formed in the casing and has a mutilated pinion 26 mounted thereon, as shown in Figs. 5, 6, 8, 9 and 22. The pinion 26 is made heart-shaped to more readily conform to the limited space to which it is restricted in its rocking movement. This pinion is provided with a number of teeth 27 positioned to be engaged by teeth 28 formed on the edge of the rounded plate-part B of the movable part of the casing, as best shown in Figs. 8, 9 and 23. The pinion 26 is provided with a guide lug 29 which is adapted to bear against and ride on the edge 30 of the casing part B. At the same time the periphery *a* of pinion 26 has a rolling bearing on the cut-away flat surface 31 of the casing part B, Figs. 5, 6, and 23. By this means these parts are accurately retained in their true working position and the axial rock-shaft 8 prevented from having a back end-wise movement. A collar 32 is rigidly mounted on shaft 8 between the pinion 27 and the disk 10. In assembling the parts, the rock-shaft 8 is inserted endwise from the chamber 25 and in order to make this possible, the opening *b* in the casing A is of a somewhat greater diameter than the shaft so that the latter can be tilted a little in entering the same. The diameter of the collar 32 is the same as that of the opening *b*, and when the shaft 8 is inserted the pinion 26 comes to a stop against the adjacent walls of the casing and prevents the shaft from entering too far and accurately positions the same and facilitates the operation of assembling.

The normal position of pinion 26, shown on Fig. 8, and the abnormal position shown in Fig. 9, correspond to similar positions of the parts shown in Figs. 10 and 11.

The means employed to automatically return the actuating lever-handle to normal, is a spring 33 having one end inserted in a cavity 34 formed in the stationary part of the machine casing, the other end being inserted in a cavity 35 located in the movable

part of the casing. By this arrangement the spring 33 is located out of the way and positioned to quickly return the lever-handle to normal after each operation.

The tens-wheel 5 is chambered on the units-wheel side for the insertion of a disk 36, as best shown in Fig. 21. This disk is also shown in Figs. 17 and 18 and is rigidly mounted on axial-shaft 8. This disk has a pin 37 loosely inserted therein which is backed by an actuating spring 38. This endwise yielding pin is positioned to engage the notches 39 formed in the inner circumferential surface 40 of the tens-wheel, and when not in engagement with one of said notches it is compressed against the tension of spring 38 and bears against the surface 40 until an impulse movement of the tens-wheel brings the next notch into position to be engaged thereby in regular order of succession.

The tens-wheel 5 turns in the direction indicated by an arrow in Fig. 17 and when in its exact normal printing position the back wall of notch 39 bears against the adjacent side of pin 37, as best shown in Fig. 17. In practical working it is possible that the tens-wheel with the impulse movement may pass the normal position but will return and stop against pin 37.

The disk 36 also has a loose locking bolt 41 inserted therein which lies in a plane parallel to pin 37 and both being positioned diagonally with reference to the axis of motion. A collar 42 is an integral part of the units-wheel and extends over and surrounds the hub 43 of the disk 36. This collar is cut-away at one point in its periphery to form a gap or low part 44, as shown in Figs. 16 and 21. When the inner end of bolt 41 rests in the low gap 44, the opposite end is out of engagement with the particular notch, of the series of notches 39, in line therewith. When the inner end of bolt 41 rests on the high part 45 of the collar 42, the outer end is in position to be in engagement with one of the notches 39, as shown in Fig. 17. These parts are so timed with relation to each other that the pin 37 will first engage one of the notches 39 in the tens-wheel and position the same should the vibration of the movement carry it a little past its true position and stop it on the come back, the bolt 41 coming into engagement at the proper time to lock the tens-wheel and hold the numbering or printing surfaces in the exact position to make a clear and complete impression which is an essential requirement in this device.

The disk 36 is provided with a rim flange 46 which has a gap 47 therein between the beveled ends 48 and 49. An impulse movement dog 50 comprises an engaging hook-end 51, a flattened stem 52 and a pivot-pin 53 turned at right angles to the hook and stem-parts, as best shown in Fig. 20, and

also shown in Fig. 16, 17 and 21. The units-wheel is provided with an aperture 54 (Fig. 12) for the inserting of the pivot-pin 53 in retaining the dog 50 in its operative position. The units-disk is provided with a recess 55 in which the stem-part 52 of dog 50 is seated and allows for the operative swinging movement of the free hook-end thereof. It will be understood that a duplicate of disk 36 and the movement dog 50 are used in connection with all of the numbering-wheels, except the last one, in transmitting an impulse movement from one to the other at the proper time. The movement dog shown is attached to the units-wheel and transmits the required impulse therefrom. Each of the numbering-wheels carrying a movement dog, are provided with an aperture 54 for the insertion of the pivot-pin 53. The disk 36 is provided with a cam-lug 57 which is located in the path of the free hook-end 51 of the movement dog 50.

Once in each revolution of the units-wheel 25 and when the gap 47 in the rim-flange 46 comes into coincident relation with the free hook end of dog 50, the latter comes in contact with the cam-lug 57 and is moved into engagement with one of the notches 39 in the tens-wheel and imparts a single impulse thereto. When the dog 50 passes on out of contact with cam-lug 57, the hook end thereof comes in contact with the beveled end 49 of the rim flange 46 and is thereby thrown out 35 of engagement with the tens-wheel which will remain stationary on disk 36 until the units-wheel completes another revolution.

A curved ratchet-plate 58 is located inside of and rigidly secured to the stationary part 40 of the casing, as shown in Figs. 5 and 6. The plate 58 is provided on its inner concave edge with two series of short teeth 59 and 60 divided centrally by a long tripping tooth 61. A pawl 62 has a rocking movement on a pivot-pin 63 which secures the same to the lever-handle part in its working position. This pawl is provided on its upper end with two teeth, 64 and 65 spaced apart, and positioned to engage the teeth 59 in the ratchet-plate 58. The lower end of pawl 62 is cut-away to present two inclined angle sides 66 and 67 converging to a common point 68. One end of a rod spring 69 has a tension coil on a fixed pin 70. The 55 free bent end 71 of this spring is always alternately in contact with either one or the other of the angle sides 66 and 67 in accordance with the position of pawl 62 consequent with the actuating movement of the lever-handle. When all the machine parts are in the normal position shown in Fig. 5, the tooth 64 of pawl 62 is in stop engagement against one side of the long tooth 61 of the ratchet-plate 58. Corresponding to 60 this position the bent end 71 of spring 69 is

in contact with the angle side 67 of the pawl 62 and the tooth 65 in engagement with the first tooth of the series 59 in the ratchet-plate 58. Now, as the lever-handle is started inward on its actuating movement 70 the tooth 65 comes into engagement with each of the series of teeth 59 in regular order until it strikes the long tooth 61 of the ratchet-plate 58 and trips the pawl 62 and throws the lower end of the same over into 75 the position shown in Fig. 6 and brings the bent end 71 of spring 69 in contact with the opposite angular side 66 thereof. Corresponding to this the lever-handle is in its innermost closed position. When the pressure on the lever-handle is relaxed the same is returned to its open normal position by the spring 33. With this movement the tooth 64 of pawl 62 engages the series of 80 short teeth 60 in regular order and prevents the lever-handle from being moved inward before it has first been returned to its full open position. With the open position the tooth 64 strikes the lug tooth 61 and throws the pawl 62 back to its normal position 85 shown in Fig. 5.

A lever 72 is located in the lower part of the machine and is mounted near its longitudinal center, on a fulcrum pin 73 and on which it has a rocking movement, 95 as best shown in Figs. 5 and 6. One end of a link 74 is mounted on a pivot-pin 75 fixed in the plate-part A of the lever-handle; the other end of said link being connected to the rear end of lever 72 by a pin 76. The 100 jaw-part 77 has an opening 78 extending upward therethrough and in which a die-punch member 79 is loosely inserted and has a reciprocating movement therein. This die-member is provided with an opening 80 in which the outer end 81 of lever 72 is loosely inserted. The female die-member 82 is located in the upper jaw-part 83 and is provided with an aperture 84 through which the cut out portion of an object 105 inserted in the ticket slot 85 escapes into the discharge passage 86. The male die-member 79 is provided with the punch-point 87 which perforates the ticket or other object inserted between the rigid jaws 77 and 83 110 which are an integral part of the front end of the stationary casing member A.

An impression-plate 88 is provided with a slot 89 starting in from the underside and stopping short of the top, as best shown in 120 Figs. 12, 13, 14 and 15. The lever 72 extends through the slot 89 of the impression-plate and is secured thereto by a pin 90, as shown in Figs. 5 and 6. The plate 88 is provided with a serrated contacting face 125 or surface 91 so as to insure a positive impression and bring out the characters imprinted clear and sharp so that a thick or thin ticket may be used. This feature is brought out in Fig. 13, which shows a 130

ticket 92 inserted and the impression-plate forcing the same squarely up against the printing faces 93. The two vertical side walls 94 and 95 of the impression-plate 88, 5 bear against the adjacent walls 96 and 97 of the stationary part of the casing and act as a guide therefor in retaining the impression-plate in a true position.

The lever 72 and all the parts connected therewith and actuated thereby, are shown in their normal position in Fig. 5, and in their opposite position in Fig. 6. The operation of these parts being as follows: When the actuating lever-handle is compressed the 5 inner end of lever 72 is forced downward and the outer end moved upward carrying therewith the punch-die and the impression plate is the operation of canceling and numbering the ticket. It will be noted that 0 in the normal position of these parts the link 74 rests in an inclined position, so that the pivotal connections of the pin 2, the pin 75 and the pin 76 are relative to the points of two sides of an equilateral triangle, and 5 when these parts are actuated they exert a powerful leverage within a compact space. The series of numbering wheels show skeleton numerals 98 having a sharp edge outline so as to insure a clear distinct impression 0 even when the inking pad is dry or partially so. This clear cut impression is made possible by the heavy pressure exerted by the lever 72 and the long angular leverage connection between the points 2 and 75, makes the use of a short handle possible and gives a distinct impression whether the ticket is thick or thin and without ink on the printing surfaces.

The punch-die is located in advance of 0 the numbering mechanism and does not punch out any portion of the numbered part of the ticket.

The casing is provided with companion lugs 99 in which the respective ends of a 5 hinge-rod 100 is secured, as shown in Figs. 2, 3, 4, 7, 8, 9, 10, 11, 12, 13, 14 and 15. An inking-pad 101 is movably hinged on this rod. A compression spring 102 is coiled on rod 100 and has one end 103 bearing 0 against the inking pad and holds the same in its innermost position against the printing surfaces of the numbering-wheels. A cam 104, is mounted on the front end of axial-shaft 8, as shown in Figs. 5, 6, 14 and 15. The inking-pad is provided with an inward projecting lug 105 which is adapted to have contact with the peripheral edge 106 of cam 104. The operation is as follows: As 5 shown in Fig. 14, the lug 105 is out of engagement with the cam 104 and which is the normal position. When the actuating lever is pressed inward the cam is turned into engagement with the lug 105 and the inking pad forced outward away from contact with 0 the numbering wheels during the turning

movement of the same and prevents the pad from dragging thereon, as shown in Figs. 13 and 15. When the parts return to normal the pad is again in contact with and inks the printing surfaces.

A plate 107 is loosely retained in the casing and is provided on its inner side with a rib 108 having a contracted edge. This plate is also provided with a lug 109 projecting into the path of the cam 104 so as to have 70 an intermittent contact therewith. The purpose of this plate 107 is to provide an additional means for positioning the numbering wheels. The rib 108 is of a length to engage all of the numbering wheels and assist 75 in locking the same in their exact printing position, as shown in Fig. 13. The end 110 of spring 102 bears against the outer side of plate 107. Normally the lug 109 is in engagement with the cam 104, as shown in Fig. 80 14. When the actuating lever is forced inward the cam rolls around out of contact with lug 109 to the position shown in Fig. 85 15. This position corresponds to the position shown in Fig. 13, the spring pressed plate 107 being forced inward and the rib 108 engaging the continuous groove 111 formed when the groove in each of the numbering wheels is in alignment.

A plate 112 is rigidly secured in place and 95 has its inner end recessed in the casing to close the opening made by the teeth 28, the cut-away edge 30 and the pinion 26.

The units and tens numbering wheels have a somewhat peculiar action or movement in practical working. There are a number of reasons for this. One is, that the dimensions and weight of the device must be kept within certain limits to be acceptable for practical use. In order to comply 100 with this requirement certain movements had to be provided for within a compact space, such as to permit of the insertion of a ticket, the inking of the printing faces and the impulse movement of the numbering 105 wheels to a higher consecutive number.

The operation to bring about this desired result is as follows:

The normal position of the movement pin 14 and the locking-pin 17 are shown in Fig. 115 10. In this position it will be noted that the locking-pin 17 rests on the back of the units-wheel and approximately mid way between two of the ratchet-teeth, as shown in Fig. 10. Now, when the actuating hand-lever is moved inward to the punching and printing position, all of the numbering-wheels turn together at the same time until the units wheel has turned far enough to bring the face 22 of the next succeeding 120 ratchet-tooth against the locking-pin 17 as shown in Fig. 11, which halts the units wheel at this point after having made a one-half impulse turning movement. The rest 125 of the numbering-wheels continue to turn 130

and make a full movement and stop when the handle-lever has reached its inner movement limit. When the units-wheel is halted by the locking-pin 17 the movement-pin 14 is in the engaged position, shown in Fig. 11, and ready to turn the units wheel to normal. When the pressure on the handle-lever is relaxed all of the numbering wheels start simultaneously on the return to normal. This 10 is the regular continuous action until it is time to advance the tens-wheel to the next highest number with reference to the units-wheel. This is done by means of the dog 50 carried by the units-wheel and the parts 15 associated therewith. It will be understood that all of the numbering wheels, except the units-wheel and the tens-wheel at predetermined intervals, have a rocking turning movement equal to one and one-half impulse 20 movement, the operation being as follows: When the lever handle is pressed inward all of the numbering-wheels turn backward, that is, in the opposite direction from the forward movement indicated by the arrow 25 in Fig. 10. As this back movement progresses the face of the ratchet-tooth next in order comes in contact with the locking-pin 17 and halts the units-wheel, the rest of the wheels continue to turn to the full 30 movement. Once in each revolution the tens-wheel is halted in position with the units-wheel by the free hook-end 51 of dog 50 engaging one of the notches 39 on the back movement, the disk 36 continuing the 35 full rocking movement, with the axial shaft 8. The free hook-end 51 of dog 50 is thrown into engagement with one of the notches 39 in the tens-wheel by the cam 57 coming in contact therewith at the proper time. As 40 the cam passes out of contact with the dog, as shown in Fig. 17, the beveled end 49 of the rim 40 comes in contact with the dog and forces the same away from engagement with the tens-wheel and it gravitates to the 45 normal position shown in Fig. 16. At the time the dog 50 is disengaged, the pin 37 is moved into engagement with the next succeeding notch of the series 39 by its actuating spring 38. The pin 37 serves to position 50 the tens-wheel. When the dog 50 is in its engaged position, the inner end of the locking-bolt 41 rests in the low part 44 of the collar 42 which is its disengaged position. As the dog 50 moves away from its 55 engaged position, the high part 45 of collar 42 comes in contact with the bolt 41 and moves the same into engagement with the same notch just vacated by the dog 50, as best shown in Fig. 17.

60 By this arrangement the disk 36 has a limited rocking movement that imparts a turning movement to all of the numbering-wheels, except the units wheel, that equals a one and one half impulse movement. The 65 relative position of the printing faces with

reference to the inking pad and the horizontal printing line is shown in Fig. 12. One of the printing faces is shown squarely in position against the inking pad. From this position it will be seen that it is necessary to make one and one half impulse movement to bring the printing face that is being inked down to the printing line. If this one and one half impulse movement was not provided for it would be necessary to extend the inking pad down so far that it would interfere with a free insertion of a ticket in the ticket-slot.

Having thus described my invention, what I claim is:

1. In a combination ticket-punch, a casing comprising a stationary-part and a movable part having a pivotal turning movement thereon, said stationary-part being provided with rigid jaws spaced apart by a ticket-slot, said movable-part being provided with an actuating lever-handle, a series of numbering wheels axially mounted, means for pressing a ticket or other object inserted in said slot against said wheels, and means for punching out a portion of said ticket other than the numbered part, simultaneously with the operation of numbering the same.

2. In a combination ticket-punch, a casing comprising a stationary and an actuating movable-part, said stationary-part being provided with a barrel-part and rigid jaws on the front end thereof, said jaws having a ticket-slot therebetween, a series of numbering wheels axially mounted in said barrel-part, a punch-die located in advance of said wheels, an impression-plate, and means for simultaneously imparting an operative movement to said die and impression-plate.

3. In a combination ticket-punch, a casing comprising a stationary part and a movable-part having a pivotal turning movement on the stationary-part, a link-member having one end pivoted to the movable-part of said casing, said link-member and rocking-lever being inclosed within said casing and having a pivoted connection with each other, a punch-die and an impression-plate mounted on the front end of said lever, and an actuating lever-handle connection.

4. In a combination ticket-punch, a casing consisting of two parts provided with integral manipulating handles, a rocking lever, a compression-plate having a pivotal connection therewith, a series of numbering-wheels, a punch-die carried by said lever and positioned in advance of said plate, and means for imparting an actuating movement to said rocking-lever.

5. In a combination ticket-punch, a casing, an actuating lever-handle provided with a plate-part pivoted to the stationary part of said casing, a rocking-lever, a punch-die and an impression-plate carried thereby, a link-

member pivotally connecting said plate-part and rocking lever, the normal position of said pivotal connections being relatively the points of two sides of an equilateral triangle.

6. In a combination ticket-punch, a casing comprising a stationary and a movable-part having a pivotal turning movement on the stationary-part, a link-member having one end pivoted to the movable part of said casing, a rocking-lever, said link-member and rocking-lever being inclosed within said casing and having a pivotal connection with each other, a punch-die and an impression-plate mounted on the front end of said lever, and an actuating lever-handle connection.

7. In a combination ticket-punch, a casing consisting of two parts provided with integral manipulating handles, a rocking lever, a compression-plate having a pivotal connection therewith, a series of numbering-wheels, a punch-die carried by said lever and positioned in advance of said plate, and means for imparting an actuating movement to said rocking-lever.

8. In a combination ticket-punch, a casing having an extended front barrel-end, a series of numbering wheels axially mounted therein, an actuating lever-handle, and the means described for operatively connecting said lever-handle with said numbering wheels.

9. In a combination ticket-punch, a two-part casing having an extended front-end, an axial shaft mounted therein, a series of numbering-wheels mounted thereon, a pinion mounted on the inner end of said shaft, an actuating lever-handle connected with a movable part of said casing, and means for operatively engaging said pinion coincident with the actuating movement of said lever-handle.

10. In a combination ticket-punch, a casing having an extended front barrel-end, a series of numbering wheels axially mounted therein, an actuating lever-handle, and the means described for operatively connecting said lever-handle with said numbering wheels.

11. In a combination ticket-punch, a two-part casing having an extended front-end, an axial shaft mounted therein, a series of numbering-wheels mounted thereon, a pinion mounted on the inner end of said shaft, an actuating lever-handle connected with a movable part of said casing, and means for operatively engaging said pinion coincident with the actuating movement of said lever-handle.

12. In a combination ticket-punch, a casing comprising a stationary part and a movable part pivotally joined together, an axial shaft having a rocking movement and located in the extended front end of the stationary part of said casing, mutilated pin-

ion mounted on the inner end of said shaft, an actuating lever-handle, and means carrier by the movable part of said casing for engaging said pinion and transmitting a rocking movement to said shaft.

70

13. In a combination ticket-punch, a casing having a movable part provided with teeth on one edge thereof, an axial shaft, a mutilated pinion mounted on the inner end of said shaft and adapted to be engaged by said teeth, said pinion being provided with a guide lug, positioned to engage said edge adjacent to said teeth and lock said axial shaft against back movement.

75

14. In a combination ticket-punch, a casing, an axial shaft, a units-wheel having a ratchet wheel formed integral therewith and loosely mounted on said shaft, a movement-disk rigidly mounted on said shaft and seated in said ratchet-wheel, a spring actuated movement-pin loosely inserted in said disk and positioned to engage the teeth of said ratchet-wheel in regular order of succession and transmit a single impulse to said units wheel, a spring actuated locking-pin loosely inserted in the casing and positioned to engage the teeth of said ratchet-wheel and lock the units-disk against back movement, and means for rocking said axial shaft.

80

15. In a combination ticket-punch, a casing having a movable part provided with a number of teeth and an actuating handle, an axial-shaft, a mutilated pinion mounted thereon and positioned to be engaged by said teeth, a units-wheel provided with a ratchet-wheel and loosely mounted on said axial-shaft, a movement-disk rigidly mounted thereon, means carried by said disk for engaging said ratchet-wheel and imparting an impulse movement thereto, and means for engaging said ratchet-wheel after each impulse movement and locking the units-wheel against a back movement.

95

16. In a combination ticket-punch, a casing having a movable part and provided with a number of teeth on one edge thereof, an axial-shaft carrying the numbering wheels and having a mutilated pinion mounted on its inner end and provided with a guide-lug adapted to bear on the edge of said casing adjacent to said teeth in retaining these parts in close working relation.

100

17. In a combination ticket-punch, a casing provided with a movable part carrying an actuating handle, an axial-shaft, a units-wheel loosely mounted thereon and provided with a ratchet-wheel integral therewith, a movement-disk rigid on said shaft, means for operatively connecting said units-wheel and movement-disk, and means for rocking said axial-shaft.

115

18. In a combination ticket-punch, an axial-shaft, a units-wheel provided with ratchet-teeth and loosely mounted thereon, 130

120

a movement-disk rigid on said shaft, a spring actuated movement-pin carried by said disk and positioned to yieldingly engage said teeth and transmit an impulse 5 movement to said units-wheel at the proper time.

19. In a combination ticket-punch, a casing comprising a stationary-part and a part having a pivotal movement connection therewith, an axial shaft capable of reciprocating rocking movement, a movement-disk rigidly mounted thereon, a units-wheel loosely mounted and provided with ratchet-teeth overlapping said disk, a movement-pin carried by said disk, means for actuating said pin, and means for locking the units-wheel against back movement after each impulse.

20. In a combination ticket-punch, a casing comprising a stationary part and a movable-part, an axial shaft, a units-wheel loose thereon and provided with ratchet-teeth, a movement-disk rigid on said shaft, a movement-pin seated in said disk and adapted to engage said teeth in regular order of succession, and a locking-pin inserted in the stationary part of said casing and locking the units-wheel against back movement.

21. In a combination ticket-punch, a casing, an axial-shaft, a disk rigidly mounted therein, a tens-wheel turning on said disk and provided in the inner circumferential surface with a series of notches, a spring actuated pin seated in said disk and positioned to engage said notches in regular order, a locking-bolt loosely inserted in said disk and having a free endwise movement, and means for moving said bolt into and out of engagement with the tens-wheel at predetermined intervals.

22. In a combination ticket-punch, a casing, an axial-shaft, a disk rigidly mounted thereon, a tens-wheel loosely mounted on said disk and provided with a series of notches, a spring actuated pin seated in said disk and positioned to engage said notches in regular order, a locking-bolt loosely inserted in said disk, units-wheel provided with a collar on which the inner end of said bolts ride, said collar having a high and low-part, the high part holding the outer end of said bolt in engagement with said notches and out of engagement when the inner end rests in the low-part.

23. In a combination ticket-punch, a casing, an axial shaft, a disk provided with a rim flange having a gap therein and rigid

on said shaft, a tens-wheel provided with a series of notches, a spring actuated pin, a locking-bolt, a units-wheel, a movement dog 60 connecting said tens and units-wheels, and means for throwing the free end of said dog into and out of engagement with said notches at the proper time.

24. In a combination ticket-punch, a 65 curved ratchet-plate provided with a number of teeth of equal length divided into two series by a longer tripping-tooth, the stationary part of the casing to which said plate is rigidly secured, the movable part 70 of the casing, a pawl pivoted thereto and provided on the upper end with companion teeth and adapted to engage the teeth in said ratchet-plate, said pawl being provided on the lower end with angle sides, and a 75 spring having an alternating contact therewith.

25. In a combination ticket-punch, a casing, an axial-shaft, the numbering-wheels mounted thereon, an inking-pad normally 80 in contact with said shaft for momentarily moving said pad away from its inking position, and means for returning the same to its inking position.

26. In a combination ticket-punch, a cas- 85 ing having a movable part provided with teeth on one edge thereof, an axial shaft, a mutilated pinion mounted on the inner end of said shaft and adapted to be engaged by said teeth, said pinion being provided 90 with a guide lug, positioned to engage said edge adjacent to said teeth and lock said axial shaft against back movement.

27. In a combination ticket-punch, an axial shaft having a rocking movement, a 95 disk rigidly mounted thereon, a spring-actuated pin inserted in said disk, a locking-bolt carried by said disk, a units-wheel provided with a collar having a low part in which the inner end of said low-part normally 100 rests, a tens-wheel provided with a series of notches with which said pin and bolt are adapted to engage at predetermined intervals, an impulse movement dog carried by said units-wheel, and means for throwing 105 said dog into and out of engagement with the tens-wheel at the proper time.

In testimony whereof I affix my signature in presence of two witnesses.

WILLIAM C. DOWNING.
